DISPENSER

Harold F. Johnston and Emerson H. Tompkins,
Waterbury, Conn., assignors to Scovill Manufacturing Company, Waterbury, Conn., a corporation of Connecticut

Application June 15, 1936, Serial No. 85,286

2 Claims. (Cl. 215—78)

This invention relates to improvements in dispensers such as are used as stoppers for containers and relates more particularly to that type of dispenser adapted to be positioned in the neck of a bottle and employing a depressible plunger that normally projects slightly above the closure cap and whereby limited quantities of liquid can be released as into the palm of a hand by slightly pressing in on the plunger.

10 The invention further relates to dispensing means such as are adapted to be used for the closure of receptacles such for instance as bottles and employed for containing face and hand lotions or other toilet preparations, condiments, or the like. Our dispenser is of the gravity type, which is provided with a discharge opening that is normally closed but which may be manually opened when the container is inverted and its conical plunger pressed in more or less according 20 to the quantity of liquid desired.

An object of the invention is to provide a simple and practical form of dispenser which may be manufactured largely from sheet metal, quickly assembled and conveniently attached, as by threads, to the mouth of a bottle; further to provide a dispenser which will permit the liquid to freely flow therethrough when the container is turned bottom up to dispense the liquid when 25 pressed against an object such as a person's hand.

A further object of the invention is to include a depending tubular casing having an annular external flange around its upper end portion, that is secured as between the cap and a packing covering the mouth end of the bottle and which casing is provided with a perforated bottom adapted to support a spring that actuates the plunger.

Another important feature of the invention is 40 to provide a construction which may be readily assembled so that the parts may be held together temporarily for shipping purposes by means of one of its elements such for instance as a sealing washer and which is adapted to be 45 permanently held in an operable assembled position coincident with the assembly of the cap upon the mouth of a bottle or container.

Our invention further consists in the constructions and in the interrelations and combination of parts hereinafter described and more particularly pointed out in the claims and as will be more readily understood by referring to the accompanying drawing forming a part of this specification, and in which

55 Fig. 1 shows, on a slightly enlarged scale, a

central vertical section through our improved type of dispenser shown attached to the mouth portion of a bottle and wherein the metal plunger is provided with peripheral guides.

Fig. 2 is a detached bottom plan view of the 5 dispenser shown in Fig. 1.

Figs. 3 and 4 show a top plan view, and cross section respectively taken on line 7—7 of Fig. 3, illustrating a shell form of plunger as shown in Fig. 1.

10 In the drawing 10 represents a bottle neck provided with a thread 11 to receive the rolled threads 12 in the depending annular flange portion 13 of a closure cap 14. This closure cap is formed of sheet metal of a size to snugly fit 15 and close the bottle and inclose the other elements of the dispenser including the conical plunger 15 which normally extends out through a central opening 16 in the top of the raised portion 17 of the cap 14. This plunger is normally retained in its raised position by means of a spiral spring 18a the upper end portion of which is seated against the underside of the plunger and the lower end of which rests on the lower internal annular ledge portion 19 of the 25 cylindrical support 20 that is disposed into the neck of the bottle. The upper end of this support is provided with an outwardly disposed annular flange 21 that is engaged by the inner face of the annular shouldered portion 22 of the 30 cap and secured as between it and the packing washer 23 that covers the end of the bottle and extends in against the outer wall of the cylindrical portion of the support better to support and center the same.

35 In the drawing, as will be seen, the plunger is provided on its lower edge portion with spaced apart guide members 25a, against which the upper end of the spring 18a is positioned. The depending end portions of these guide members 40 25a are disposed in the cylindrical support in a way to slidably engage the inner wall thereof to permit the lower portion of the plunger to be pressed down into the casing against the action of the spring and thus produce an annular opening in the cap surrounding the tapered plunger in a way to allow the liquid to pass out, through the dispenser. In this dispensing operation the liquid passes from the bottle into the lower end of the casing, past the lower edge portions of the plunger into the chamber 26 of the closure cap and out through the opening, that is of course when the bottle is turned bottom up and the plunger is pressed inward. Due to the 55

use of a conical plunger in a given size of round hole it will be apparent that the size of the outlet produced by the pressing in of the plunger will depend upon the amount of pressure applied 5 when operating the plunger.

Having thus described our invention what we claim and desire to secure by Letters Patent is:

1. A liquid dispenser of the class described including a closure cap adapted for attachment to the open end of a container and having a discharge opening therein, a support member extending within the open end of said container and having means to permit the passage of the container contents therethrough, means for holding 10 said support member in cooperable assembled position relative to said cap coincident with the assembly of the latter to its respective container and a plunger for closing the opening in said cap having integrally formed spaced guide fingers 15 slidably engaged in said support member, and a spring engaged between the support means and

the plunger for holding the latter in normal closed position.

2. A liquid dispenser of the class described including a closure cap adapted for attachment to the open end of a container and having a discharge opening therein, a support member extending in the open end of said container and having means to permit the passage of the container contents therethrough, means for holding the support member in cooperable assembled 10 position relative to said cap by the assembly of the latter to its respective container, a hollow conical shaped plunger, said plunger provided at its base end with integral outwardly formed spaced fingers having slidable guiding connection 15 with said support, and a coiled spring compressed between said fingers and said support for normally holding said plunger in closed position in said opening.
